UNITED STATES PATENT OFFICE.

KARL KEMPNY, OF CLEVELAND, OHIO.

ARMORED AUTOMOBILE.

1,282,235.

Specification of Letters Patent. Patented Oct. 22, 1918.

Application filed December 18, 1916. Serial No. 137,633.

To all whom it may concern:

Be it known that I, KARL KEMPNY, a subject of the Emperor of Austria, residing at Cleveland, in the county of Cuyahoga and State of Ohio, have invented certain new and useful Improvements in Armored Automobiles, of which the following is a specification.

This invention relates to armored automobiles and has special reference to an armored automobile provided with improved means for repelling infantry attacks.

One object of the invention is to improve the general construction of devices of this character.

A second important object of the invention is to provide a device of this character having improved means for protecting the rapid fire guns used in connection with the device from injury by bullets, shell fragments and the like.

A still further object of the invention is to provide an armored automobile having an improved arrangement of sword bayonets extending along its sides and serving to repel attempts to climb on the machine as well as to cut through opposing troops and such obstacles as barbed wire and the like.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:

Figure 1 is a side elevation of an improved armored automobile constructed in accordance with this invention.

Fig. 2 is a plan view thereof.

Fig. 3 is a longitudinal section therethrough.

Fig. 4 is a rear elevation of the machine.

Fig. 5 is a fragmental detail showing a portion of a platform used herewith and the manner of attaching bayonets thereto for folding out of the way when not in use.

Fig. 6 is a section on the line 6—6 of Fig. 5.

Fig. 7 is a side elevation of one of the bayonets and the part to which it is attached, the locking ring being shown in section.

Fig. 8 is a section on the line 8—8 of Fig. 1.

In carrying out the objects of this invention there is provided an armor casing the body of which is indicated at 10 and this casing has its forward upper portion rounded and inclined rearwardly at 11. Moreover, on each side of the casing there is provided a sponson 12, the opening 13 of which is closed by an arcuate movable shield 14 having a tubular projection 15 extending outward therefrom.

This casing or body is supported on wheels 16 which receive their power from a suitable motor, not shown, inclosed in a motor housing 17 at the forward portion of what may be termed "the deck" of the armored car. Moreover, there is provided in this forward portion the usual driver's seat 18 and steering wheel 19.

Extending forwardly from each side and the front of the car are frames 20 and the three frames 20 support a longitudinally curved plate 21 the front end of which is raised well above the ground while the rear end of the plate extends beneath the body and is spaced slightly above the ground. This plate is for the purpose of crushing down such obstacles as barbed wire entanglements and the like and also acts as a deflector of bullets striking the plate, said bullets being deflected downward so as to prevent their striking the front end of the car and possibly penetrating the same. In this manner the body of the car is well protected from fire from in front. Furthermore, this plate enables the car to pass trenches and shell holes since even if the front wheels are not on the ground as in passing a trench, the plate will reach across to the other side of the trench and ride up on the edge of the trench whereupon the front wheels can gain the ground and perform their usual functions.

At each side of the car, on a level with the bottom or deck, there is provided an outwardly extending platform 22 which tapers from front to rear, coming to a point at the front end and being brought enough rearwardly to include the sponson on the respective side.

Mounted in brackets 23 pivoted to these platforms adjacent their edges are shafts 24. Similarly, shafts 25 are mounted one above the other on the sides of the car forward

and aft of the sponsons. Each of these shafts is provided with a series of extensions 26 each carrying a lug 27 and on these extensions are fitted the socket ends 28 of 5 sword bayonets 29, the lugs being slidable in slots 30 in the sockets and the socket being locked on the extension by the usual locking ring 31.

On each of the sponsons there is provided 10 a series of foldable projections 32 similar to the projections on the shafts and like them carrying bayonets 33. In order to rotate these shafts and fold up the bayonets to inoperative positions each of the shafts is provided 15 with an operating handle 34 which, when the shafts are folded up are engaged by fastening loops 35 pivoted in convenient position to drop over the operating handles when the bayonets are in folded position.

20 On top of the body of the car there is provided a conning hood or tower 36 having the usual sight openings 37. Similarly on the inclined forward end 11 there is a conning hood 38 provided with sight openings 39. 25 On each of the sponsons there is a frustoconical cover 40 provided with sight openings 41 which are so distributed as to give a range of sight from dead ahead to dead astern. Moreover, the sides of the car are 30 provided with slits 42 for rifle fire and observation as shown in Fig. 1.

In each of the sponsons is a rapid fire gun 43 and suitable arm and ammunition chests 44 are provided at convenient places 35 within the car. It will be noted that access is had to the car through a rear door 45 and that forward of the sponsons there is ample room for the storage of various sorts as well as for the accommodation of the crew.

40 In ordinary use, when not in actual battle, the different bayonets may be removed from their projecting lugs and the car used to transport men or munitions, the platforms serving to hold the men or munitions and 45 thus increasing the capacity of the car. In the battle front it is preferred to keep the bayonets in position on their projections and when in actual battle the bayonets are of course turned down to a horizontal position. 50 However, the upper rows of bayonets, may, if desired be turned up so as to afford additional room for soldiers, as for instance, the rear ends of the platforms behind the sponsons may shelter several men. When making a charge with the car all of the bayonets 55 will of course be turned down to horizontal position.

It will further be noted that the arrangement of the machine gun is such that its barrel, instead of projecting outward beyond

the armored portion of the car projects into the tubular extension 15 of each sponson shell so that it is protected from rifle bullets and ordinary shell fragments. Moreover, this arrangement is such that the discharge 65 of the rapid fire gun sets up a current of air in the tube 15 which acts to blow away the smoke and fumes and keep the tube clear so that such smoke and fumes do not blow back into the car.

70 There has thus been provided a simple and efficient device of the kind described and for the purpose specified.

It is obvious that many minor changes may be made in the form and construction 75 of the invention without departing from the material principles thereof. It is not therefore desired to confine the invention to the exact form herein shown and described but it is wished to include all such as properly 80 come within the scope claimed.

Having thus described the invention, what is claimed as new, is:—

1. The combination with a wheel supported armored car body; of a multiplicity 85 of bayonets having hinged connection to the sides of the car body.

2. The combination with the wheel supported armored car body; of rods extending longitudinally of the sides of said body and 90 hingedly connected thereto, spaced lugs projecting from said rods, bayonets detachably mounted on said lugs, and means to rotate the rods to move the bayonets from laterally projecting position to substantially vertical position.

3. The combination with a wheel supported armored car body having gun sponsons on its sides, of a multiplicity of laterally protruding bayonets hingedly connected 100 to the sides of the body and the gun sponsons.

4. The combination with a wheel supported armored car body; of gun sponsons mounted on the sides of said body and having ports therein, arcuate shields covering said ports and movable concentrically around the sponsons, and an armored gun barrel protecting tube projecting outwardly from 105 each of the arcuate shields, bayonets projecting laterally from the sponsons below the arcuate shields whereby to prevent interference with the movements of said shields.

In testimony whereof I affix my signature in the presence of two witnesses.

KARL KEMPNY.
